(57) **CLAIM**

The ornamental design for a windlass winch capstan, as shown and described.

DESCRIPTION

FIG. 1 is a perspective view of a windlass winch capstan; FIG. 2 is a front elevational view thereof with the right, left and rear side views being identical thereto; FIG. 3 is a top plan view thereof; and, FIG. 4 is a bottom plan view thereof.

The broken lines are for illustrative purposes only and form no part of the claimed design.
